OIL-ENGINE-FEEDING DEVICE.

1,411,025.

Specification of Letters Patent. Patented Mar. 28, 1922.

Application filed January 11, 1919. Serial No. 270,698.

To all whom it may concern:

Be it known that we, FRANKLIN G. HOBART and CHARLES B. JAHNKE, citizens of the United States, residing at Beloit, in the 5 county of Rock and State of Wisconsin, have invented a certain new and useful Improvement in Oil-Engine-Feeding Devices, of which the following is a specification.

This invention relates to that class of 10 fuel feeding mechanism for use upon oil burning engines in which, as is well understood in the art, a supply tank is used with a constant level of oil which is to be delivered to the engine. The principal object 15 of the invention is to provide, in combination with such tank, an injection pump, preferably located in the tank itself and receiving oil therefrom, to force said oil into the engine. A further object of the invention 20 is to provide, with such a tank and injection pump, a supply pump, preferably also located inside the tank, for maintaining a constant level of oil in the tank, the whole being preferably so arranged that both 25 pumps may be conveniently operated by a single operating mechanism with a minimum amount of piping and parts. A further object of the invention is to provide means by which the pumps may be operated automatically by the engine itself, or by hand, 30 if desired, and may, in the former case, be moved out of engagement with the parts of the operating engine, thereby shutting off the supply of fuel oil and stopping the 35 engine, or permitting movement of the engine by hand.

The invention consists in means for carrying out the foregoing objects, which can be easily and economically made, which is 40 simple and compact in construction, satisfactory in operation and not readily liable to get out of order. The invention further consists in other features and details which will be hereafter more fully set forth in the 45 specification and claims.

Referring to the drawings, in which similar numerals indicate the same parts throughout the several views,

Figure 1 is a vertical sectional view 50 through mechanism illustrating this invention in its preferred form, taken on the line 1-1, of Figure 2.

Figure 2 is a plan view taken on the line 2-2 of Figure 1.

Figure 3 is another vertical sectional view 55 taken on the line 3-3 of Figure 2.

Figure 4 is a vertical sectional view taken at right angles to Figure 3 on the line 4-4 of that figure.

Figure 5 is an alternative construction of 60 an essential part of Figure 4.

The device is shown applied in connection with an engine crank shaft 10, mounted in suitable bearings 12 from which is hung by suitable bolts or screws 14 the constant 65 level oil supply reservoir or tank 16, provided with a suitable cover 18. The reservoir is provided with a dam or spillway 20 over which any excess of oil 32 flows to a discharge pipe 22 leading back to an 70 original source of supply, not shown; also with a sight glass 24 through which the level of oil in the reservoir can be inspected. Oil conveyed to the bottom of the reservoir through the pipe mechanism 26, 28, shown 75 in Figures 1 and 3, is delivered into the reservoir through the supply pump cylinder 30. Pipe 22 discharges oil to the same source of oil supply, heretofore referred to, not shown in the drawing. 80

Supply pump cylinder 30 is centrally bored to provide an enlarged passage 34 and smaller passage 36 entering supply pipe 28, there being at the juncture of these passages a ball valve 38, shown in Figure 3. Reciprocatable in this passage 34 is a hollow supply pump plunger 40 resting upon a coiled spring 42 and carrying at its bottom a ball valve 44 controlling access to the interior passageway 46 within the plunger 40. In 90 the sides of this plunger 40 are ports or passageways 48 always in communication with suitable corresponding passageways 50 in the side walls of the pump cylinder 30, so that oil drawn by the supply pump from supply pipe 28 is discharged through these passageways 50 into the interior of receptacle 16. As plunger 40 is depressed, valve 38 is held on its seat and valve 44 rises from its seat so oil passes into chamber 46. When 100 plunger 40 is moved in the opposite direction ball 44 is held on its seat and the oil in the chamber is lifted and overflows through passage 50.

The suction caused by this

movement draws oil into chamber 34, past valve 38, so by properly reciprocating pump plunger 40 the level of oil 32 in receptacle 16 may be maintained constant.

5 In receptacle 16 adjacent to the supply pump is an injection pump cylinder 56 and pump is solid pump plunger 58, supported upon spring 60. Below plunger 58 is always an oil chamber 62 provided with intake opening 64, controlled by a ball valve 66 contacting the lower end of rod 68 and normally held in closed position by a spring 70. Oil space 62 is provided with discharge passage 72 closed by ball valve 74 supported by spring 76. Oil flowing from passage 72 past valve 74 enters feed pipe 78 leading to the engine or other device which is to be supplied with oil by the mechanism of this invention. Figure 5 shows an alternative construction in which passage 82, ball valve 84, spring 86 and feed pipe 88, corresponding to the parts 72-78 are located at the side of the chamber 16.

Shaft 10 carries a suitably shaped cam 90 for operating the pumps. Cam 90 operates lever mechanism 92, (pivoted on a pin or stud 94, conveniently located on a fixed support,) through engagement with roller 96. Bearing members 98 and 100 on lever 92 engage respectively the upper ends of pump plungers 30 and 58. As cam 90 reaches the position where its high point 91 engages wheel 96 on the lever 92, the lever is rocked in a counterclockwise direction about pin 94 and the pump plungers are accordingly depressed against the action of their respective springs 42 and 60. As cam 90 moves its high point 91 off from wheel 96 the springs return the pump plungers to elevated position.

Loosely journaled about crank shaft 10 is another cam 102 having its cam face 103 bearing upon one portion of another lever member 104, also fulcrumed upon pin 94. Attached to cam 102 by crank pin 106 is a rod 108 leading to the governor, not shown, of the engine, which governor is of such a type that it moves rod 108 and consequently cam face 103 backward and forward with respect to the shaft, in accordance with variations in the load on the engine.

Lever 104 has an arm portion 105 located substantially above ball valve 66. Inserted through this member 105 is an adjusting screw 112 held in more or less locked position by a spring 114. The upper end of rod 68 loosely enters the lower portion of member 105 and takes bearing against the lower end of screw 112. By rotating screw 112 the relation of the rod 68 and consequently ball valve 66 to lever 104 may be adjusted. When, in the movement of the engine, cam 102 moves lever 104 as far as it will go to the left, as viewed in Figure 1, rod 68 is moved downward, thus opening valve 66 against the ac-

tion of spring 70. This valve is held in this position until movement of the engine causes cam 102 to move to such other position that spring 70 can close valve 66.

In order to provide for hand operation of the pumps in starting the engine, and also to provide for locking the pumps in such a position that shaft 10 and cam 90 may be rotated if desired without operating the pumps, lever 92 is provided with suitably located cam faces 116 and 118 adapted to be engaged by a tooth 120 on a hand lever 122. These cam faces 116 and 118 are so arranged and shaped that as long as the operator rocks handle 122 to keep tooth 120 on cam face 116 only, he can rock lever 92 to manipulate the two pump plungers in the same manner as though they were depressed by the action of cam 90, and that when he swings the lever 122 sufficiently in a clockwise direction, as viewed in Figure 1, so that tooth 120 passes along cam surface 118, he locks the pump plungers in depressed position. In this position lever 92 is so held that roller 96 does not engage the face of cam 90, wherefore the cam can rotate freely without touching or in any way affecting roller 96, lever 92 and attached parts. In this position the pumps stop and the engine stops for want of fuel oil.

In order to insure the free operation of cam 102 during the operation of the engine without any locking or binding of cam 102 on the face of cam 90, the sleeve 124 of cam 102 is mounted upon a sleeve 126 interposed between it and shaft 10 and made slightly longer than sleeve 124 so that there is a clearance 128 between one end or the other of sleeve 124 and the adjacent parts, thus insuring free movement of cam 102.

In the complete operation of the device, main shaft 10 rotates continuously, thus rotating cam 90 continuously to, at each revolution, depress pump plungers 40 and 58 against the actions of their respective supporting springs. The operation of pump plunger 40, as described, maintains a constant level of oil 32 in chamber 16. Assume that plungers 40 and 58 are at the bottoms of their strokes and are beginning to move upward. Valve 66 is at this time held in depressed position off from its seat so that there is a free passage of oil from chamber 16 to passage 64. Upward movement of plunger 58 creates a vacuum in oil space 62 which fills by its drawing oil 32 past valve 66 from chamber 16. When plunger 58 reaches the top of its stroke oil space 62 is full and the pump is capable, if so desired, of ejecting the entire amount of oil past valve 74 (or 84, as the case may be) into the engine. The exact amount so ejected is determined by the point in the downward movement of plunger 58 at which cam 102 permits valve 66 to close, for while valve 66

is held open, oil in pump space 62 is returned past valve 66 to chamber 16. Thus without interfering with the smooth operation of the pump plunger 58, the governor of the engine through cam 102 determines just how much oil is delivered to the engine at each stroke of the pump plunger. The two pumps are located side by side in chamber 16 without the use of piping connections between them and the entire mechanism is very compact and has comparatively few moving parts. This renders the device highly satisfactory and efficient and desirable commercially.

15 The pump casing is shown separately attached to the oil chamber 16, but the method of connection is an immaterial detail.

In applying the device of this invention to a two cylinder engine, mechanism identical with that shown and described is simply added on the other side of shaft 10, with contact points of members 110 and 96 at 180° around shaft 10 from those shown in the drawing.

25 Similarly, a plurality of these mechanisms can be used for operating three and four cylinder engines, by arranging the respective operating contacts at suitable angular positions around the shaft.

30 Having thus described our invention, what we claim as new and desire to secure by Letters Patent, is:—

1. In mechanism of the class described, the combination with a constant level oil chamber, of a pair of pumps arranged within said chamber, one for supplying oil thereto and the other for drawing oil therefrom, and means for operating said pumps.

2. In mechanism of the class described, the combination with a constant level oil chamber, of a pair of pumps arranged within said oil chamber, one operable to supply oil directly thereto and the other operable to draw oil directly therefrom, and means for operating said pumps.

3. In mechanism of the class described, the combination with a constant level oil chamber, of a pair of reciprocating pumps arranged within said chamber, one for supplying oil thereto and the other for drawing oil therefrom, and means for simultaneously reciprocating said pumps in the same direction.

4. In mechanism of the class described, an oil receptacle provided with an overflow for maintaining a constant liquid level within said oil receptacle, a pair of pump cylinders located in said receptacle, of reciprocatable pump plungers mounted in each of said pump cylinders, and a single rocking member simultaneously engaging the ends of said pump plungers operable to simultaneously move the plungers in the same direction; and means for actuating said rocking member, one pump being so connected up as to deliver

oil into said chamber, the other being so connected up as to deliver oil from said chamber, for the purposes set forth.

5. In mechanism of the class described, the combination with a constant level oil chamber, of a pair of independently operating pumps arranged within said chamber, one for supplying oil thereto and the other for drawing oil therefrom, and means for operating said pumps.

6. In mechanism of the class described, the combination of an oil chamber, a pair of pumps in connection with said chamber, one delivering oil to and the other delivering oil from said chamber, and mechanism adjacent to said chamber, including a single cam connected with said pumps and operable to actuate them simultaneously.

7. In mechanism of the class described, the combination of an oil chamber, a pair of pumps in connection with said chamber, one delivering oil to and the other delivering oil from said chamber, a movable cam mechanism adjacent to said chamber, means interposed between said cam mechanism and said pump, whereby the cam mechanism operates said pumps simultaneously, and an adjustable intake valve mechanism for said second mentioned pump operable to control the amount of oil delivered thereby from said oil chamber.

8. In mechanism of the class described, a rotatable engine shaft, an oil tank adjacent thereto, a pair of pumps mounted inside of said oil chamber, one delivering oil to the chamber, the other delivering oil from the chamber, a valve controlling the admission of oil from said chamber to the second pump, a cam on the engine shaft, means interposed between said cam and said pumps whereby the cam operates the pumps simultaneously, another cam controlled by the engine governor, and means interposed between the second cam and said valve on the second pump, whereby the engine governor determines what proportion of the oil forced by said second pump is delivered outside of the oil chamber and what proportion is returned to it, for the purposes set forth.

9. In mechanism of the class described, the combination with a shaft rotated by an engine, an oil chamber adjacent to said shaft, a pair of pump cylinders within said chamber, a pair of pump plungers, a pair of springs supporting said pump plungers, one for each pump cylinder, a rocking lever engaging both of said pump plungers, a cam on said shaft engaging said rocking member to move said pump plungers in their respective cylinders against said springs, piping connections whereby one of said pumps brings in oil to maintain a constant level in said oil chamber, piping connections whereby the second pump delivers oil from said chamber to the engine, an intake valve for the second

- 5 pump located in the oil within said chamber, a valve controlling the admission of oil from the chamber to said intake opening, a cam member controlled by the governor of the engine, and means between said second cam and said intake valve on the second pump arranged to hold said last mentioned valve open during a predetermined portion of the delivery stroke of the second pump, for the purposes set forth.
- 10 10. In mechanism of the class described, an oil chamber, a pair of pumps, one adapted to deliver oil to said chamber, the other adapted to receive oil from said chamber and deliver it elsewhere, a rockable member adapted to be moved to simultaneously operate said pumps, an engine shaft, means on said shaft adapted to rock said rockable member, and a hand lever contacting said operable member in such a way that the operator may, at will, move said rockable member independently of the engine shaft and may lock said rockable member in such a position that the pumps are out of operative connection with the engine shaft, for the purposes set forth.
- 15 11. In mechanism adapted for application to an oil engine, an oil chamber, a pump adapted to receive oil from said chamber, and deliver it to any engine to which the device may be applied, a rockable member adapted to be moved to operate said pump, a cam adapted to be driven by the engine to which the device may be applied adapted to periodically engage said rockable member to operate the pump, a multiple faced cam carried by the rockable member, and a hand lever normally out of engagement with said cam adapted to be moved at the will of the operator into and out of engagement with one of said cam faces to manually operate the rockable member and the pump independently of movement of the engine to which the device may be applied, and also adapted to be alternately moved into engagement with another of said cam faces to lock the parts in such a position that the operation of the pump may be stopped.
- 20 12. In mechanism adapted for application to an oil engine, an oil chamber, a pump spring actuated in one direction adapted to receive oil from said chamber, and deliver it to any engine to which the device may be applied, a rockable member adapted to be moved to operate said pump in the opposite direction, a cam adapted to be driven by the engine to which the device may be applied, adapted to periodically engage said rockable member to operate the pump, a multiple faced cam carried by the rockable member, and a hand lever normally out of engagement with said cam adapted to be moved at the will of the operator into and out of engagement with one
- 25 of said cam faces to manually operate the rockable member and the pump independently of the movement of the engine to which the device may be applied and also adapted to be alternately moved into engagement with another of said cam faces to lock the parts in such a position that the operation of the pump may be stopped. 70
- 30 13. In mechanism of the class described, the combination of an engine shaft, a two pump device to be operated by said engine shaft, a cam on said shaft adapted to operate said pumps, a valve mechanism controlling one of said pumps, a second cam on the shaft adjacent to the first cam for operating said valve control, and a sleeve on the shaft and between it and said second cam supporting said second cam for rotation about the shaft, the sleeve being of greater length than the width of the second cam to insure freedom of action of the second cam, for the purposes set forth. 75
- 35 14. In mechanism of the class described, an engine shaft, an oil chamber supported from the bearing of the engine shaft, a pair of pumps in said oil chamber, one adapted to supply oil to said chamber, the other adapted to deliver oil from said chamber, a supply valve within said chamber adjacent to the second pump adapted to control passage of oil to and from the oil chamber and the second pump, a pair of operating levers journaled upon a suitable support adjacent to the shaft, a cam on said shaft for operating one of said levers, means on said lever to simultaneously operate said pumps as said cam rotates, a second cam reciprocatable on said shaft engaging the second lever arm, a connection between said second lever arm and the valve of the second pump, the parts controlling said valve being arranged to selectively determine what proportion of oil the second pump normally delivers at each stroke from said chamber and what proportion it pumps back into said chamber, for the purposes set forth. 80
- 40 15. In mechanism of the class described, an engine shaft, an oil chamber supported from the bearing of the engine shaft, a pair of pumps in said oil chamber, one adapted to supply oil to said chamber, the other adapted to deliver oil from said chamber, a suction valve within said chamber for the second pump adapted to control passage of oil to and from the oil chamber and the second pump, a pair of operating levers fulcrumed upon a suitable support adjacent to the shaft, a cam on said shaft for operating one of said levers, means on said lever to simultaneously operate said pumps as said cam rotates, a second cam reciprocatable on said shaft engaging the second lever arm, a connection between said second lever arm and the valve of the second pump, 100
- 45 110
- 50 16. In mechanism of the class described, an engine shaft, an oil chamber supported from the bearing of the engine shaft, a pair of pumps in said oil chamber, one adapted to supply oil to said chamber, the other adapted to deliver oil from said chamber, a suction valve within said chamber for the second pump adapted to control passage of oil to and from the oil chamber and the second pump, a pair of operating levers fulcrumed upon a suitable support adjacent to the shaft, a cam on said shaft for operating one of said levers, means on said lever to simultaneously operate said pumps as said cam rotates, a second cam reciprocatable on said shaft engaging the second lever arm, a connection between said second lever arm and the valve of the second pump, 110
- 55 120
- 60 17. In mechanism of the class described, an engine shaft, an oil chamber supported from the bearing of the engine shaft, a pair of pumps in said oil chamber, one adapted to supply oil to said chamber, the other adapted to deliver oil from said chamber, a suction valve within said chamber for the second pump adapted to control passage of oil to and from the oil chamber and the second pump, a pair of operating levers fulcrumed upon a suitable support adjacent to the shaft, a cam on said shaft for operating one of said levers, means on said lever to simultaneously operate said pumps as said cam rotates, a second cam reciprocatable on said shaft engaging the second lever arm, a connection between said second lever arm and the valve of the second pump, 125
- 65 130

- the parts controlling said valve being arranged to selectively determine at each stroke of the pump, what proportion of oil the second pump normally delivers from 5 said chamber and what proportion it pumps back into said chamber, and means for selectively adjusting the connection between the second cam and said supply valve for the second pump, for the purposes set forth.
- 10 16. Mechanism of the class described, comprising an oil chamber provided with an overflow for maintaining a constant liquid level within said oil chamber, a supply pump for maintaining oil in said chamber, a second pump taking oil from said chamber, both pumps being located partly within said oil chamber, and means for operating both pumps.
- 15 17. In mechanism adapted to be applied to an oil engine, a fuel supply mechanism comprising an oil receptacle provided with an overflow for maintaining a constant liquid level within said oil chamber, a pair of pump cylinders located in said receptacle, reciprocatable pump plungers mounted in each of said pump cylinders, means operated by the engine engaging the ends of said pump plungers to operate them, one pump being so connected up as to deliver oil into said chamber, the other being so connected up as to deliver oil from said chamber, for the purposes set forth.
- 20 18. In mechanism adapted to be applied to an oil engine, a fuel supply mechanism comprising an oil chamber provided with an overflow for maintaining a constant liquid level within said oil chamber, a pair of pump cylinders located adjacent to each other within said chamber, connections for 25 one of said pumps, whereby it supplies oil to said chamber, connections for the other pump cylinder, whereby it delivers oil from said chamber, a pump plunger for each pump cylinder, means operated by the engine to which the device may be applied for operating said pump plungers, and mechanism for varying, while the pumps are in operation, the amount of oil delivered by the second said pump, for the purposes set forth.
- 30 19. In mechanism adapted to be applied to an engine mechanism and its governor, an oil chamber, a pair of pumps mounted inside of said oil chamber, one delivering oil to the chamber, the other delivering from the chamber, a valve controlling the admission of oil from said chamber to the second pump, means whereby the engine mechanism to which the device may be applied operates the pumps, a cam controlled by the engine governor to which the device may be applied, and means interposed between said cam and said valve on the second pump, whereby the engine governor to which the 35 device may be applied determines what proportion of the oil forced by said second pump is delivered outside of the oil chamber and what proportion is returned to it, for the purposes set forth.
- 40 20. In mechanism adapted to be applied to an engine mechanism and its governor, an oil chamber, a pair of pump cylinders within said chamber, a pair of pump plungers, a pair of springs supporting said pump plungers, one for each pump cylinder, mechanism driven by the engine to which the device may be applied, operating said pump plungers against said springs, piping connections whereby one of said pumps brings in oil to maintain a constant level in said oil chamber, piping connections whereby the second pump delivers oil from said chamber to the engine to which the device may be applied, an intake valve for the second pump located in the oil within said chamber, a valve controlling the admission of oil from the chamber to said intake opening, a cam member controlled by the governor of the engine to which the device may be applied, and means between 45 said cam and said intake valve on the second pump arranged to hold said last mentioned valve open during a predetermined portion of the delivery stroke of the second pump, for the purposes set forth.
- 50 21. In mechanism adapted to be applied to an engine mechanism having a shaft and its governor, a two pump device to be operated by said engine to which the device may be applied, means whereby the engine to which the device may be applied operates said pumps, a valve mechanism controlling one of said pumps, a cam driven by the engine to which the device may be applied, governor to which the device may be applied for operating said valve control, and a sleeve on the shaft and between it and said cam supporting said cam for rotation about the shaft, the sleeve being of greater length than the width of the cam to insure 55 freedom of action of the cam, for the purposes set forth.
- 55 22. In mechanism adapted to be applied to an engine mechanism having a shaft and its governor, an oil chamber, a pair of pumps in said oil chamber, one adapted to supply oil to said chamber, the other adapted to deliver oil from said chamber, a supply valve within said chamber adjacent to the second pump adapted to control passage 60 of oil to and from the oil chamber and the second pump, means whereby the engine to which the device may be applied operates the pumps, a cam reciprocatable on the shaft of the engine to which the device may be applied, means whereby the cam controls the valve of the second pump, the parts controlling said valve being arranged to selectively determine what proportion of oil the second pump normally delivers at each 65

stroke from said chamber and what proportion it pumps back into said chamber, for the purposes set forth.

23. In mechanism adapted to be applied to an engine mechanism having a shaft and its governor, an oil chamber, a pair of pumps in said oil chamber, one adapted to supply oil to said chamber, the other adapted to deliver oil from said chamber, a supply valve within said chamber adjacent to the second pump adapted to control passage of oil to and from the oil chamber and the second pump, means whereby the engine operates the pumps, a cam reciprocatable on the shaft of the engine to which the device

may be applied, means whereby the cam controls the valve of the second pump, the parts controlling said valve being arranged to selectively determine what proportion of oil the second pump normally delivers at each stroke from said chamber and what proportion it pumps back into said chamber, and means for selectively adjusting the connection between the cam and said supply valve for the second pump, for the purposes set forth.

In witness whereof we have hereunto subscribed our names.
